UNITED STATES PATENT OFFICE

HENRY F. GOLDSMITH, OF PHILADELPHIA, PENNSYLVANIA, ASSIGNOR TO FRIED-BERGER-AARON MANUFACTURING COMPANY, OF PHILADELPHIA, PENNSYLVANIA, A CORPORATION OF PENNSYLVANIA

REEL HOLDER

Application filed November 9, 1927. Serial No. 232,014.

This invention relates to a holder for rotatably supporting a reel of material such as ribbon for display and which will permit of the unwinding of the reel for the purpose of severing therefrom sections of the material.

In devices of this character it is desirable to have the material exposed to view and at the same time to protect it from dust which would collect upon its surface. If the reel is supported to rotate about a horizontal axis, the upper portion of its circumferential surface may be covered by a strip of transparent material secured to the holder. As the material is removed the diameter of the reel decreases and if the transparent strip is secured to the holder so as to have a fixed radius of curvature, the surface of the reeled material moves inwardly therefrom. This separation of the surface of the reel from the transparent strip is objectionable for two reasons: First, a passage is produced through which dust may enter over the upper surface of the reel; and, secondly, reflection of lights from the transparent strip lowers the visibility of the depressed, and consequently darkened, surface of the material.

The object of this invention is the provision of a covering strip of the character above referred to which will be maintained in contact with the surface of the reel during the unwinding thereof.

In the drawing:

Fig. 1 is a vertical sectional view of the reel holder;

Fig. 2 is an end elevation of the right of Fig. 1;

Fig. 3 is an end elevation of the left of Fig. 1;

Fig. 4 is a section on line 4—4 of Fig. 1;

Fig. 5 is a section on line 5—5 of Fig. 3; and

Fig. 6 is an edge view of a modification.

The holder comprises two side members 2 of pasteboard or other suitable material secured to a hub 4 by securing means such as indicated at 6. The side members 2 are shown provided with flared bottoms to form a supporting base for the holder. Hub 4 is adapted to receive a reel 8 of ribbon, tape, or

the like, which reel may be rotated by a pull on the free end of the strip to deliver any desired length of the strip for the purpose of use or sale.

A narrow strip 10 of pasteboard or similar material is secured at its ends to the side members 2 as shown in Figs. 1 and 2 and has secured thereto a covering strip 12 of transparent material, which strip extends over the upper surface of reel 8 and between the reel and a second strip 14 similar to strip 10 located as shown in Figs. 1 and 3. The free end of covering strip 12 is secured, for example, by adhesive, to the outer wall of a flattened loop of pasteboard 16, through which loop the free end 18 of the strip material forming the reel is threaded.

The function of this arrangement to maintain the covering strip 12 in contact with the surface of the reel will be apparent. In the unwinding operation the strip forming the reel tensions covering strip 12 by reason of the frictional engagement of the loop 16 with the unwinding strip.

It is desirable to leave an extensive portion of the lower surface of the reel uncovered so that a finger may be inserted to contact with the reel surface as shown in Fig. 1 to rewind thereon any portion of the strip which has been unwound in excess of that desired for use or sale. If during such rewinding loop 16 is frictionally carried upward producing a bulge in the covering strip, the covering strip may be restored to proper position by a manual downward movement of loop 16.

It should be understood that the invention is not limited in its application to a reel holder of the specific construction shown, nor, indeed, to any particular type of support for the reel, so long as provisions are made for the rotation of the reel.

Nor is it intended to limit the invention to any specific means for securing the transparent covering member in position nor the specific means shown for carrying the free end of the covering member and for providing for the slideable frictional engagement between the covering member and the strip material being unwound. Thus, in place of the

flattened loop 16 may be substituted a slotted plate 20, conveniently of pasteboard, shown in Fig. 6. In this modification, the end of the covering strip 12 is adhesively secured to the rear of plate 20 above the slot, while the free end 18 of the strip material extends from the back of the plate through the slot onto the front of the plate.

What I claim and desire to protect by Letters Patent is:

- 10 1. In combination with a support upon which a reel of strip material may be rotatably mounted, a covering member for a portion of the circumferential surface of the reel and means on said covering member arranged to frictionally engage said strip material whereby unwinding of the strip material will draw the covering member into contact with the surface of the reel.
- 15 2. In combination with a support upon which a reel of strip material may be rotatably mounted, a flexible covering strip for a portion of the circumferential surface of the reel, one end of said covering strip being secured to the support and the other end of said covering strip having means arranged to frictionally engage said strip material whereby unwinding of the strip material will draw the covering strip into contact with the surface of the reel.
- 20 3. In testimony of which invention, I have hereunto set my hand, at Philadelphia, Pennsylvania, on this 7th day of November, 1927.
- 25 4. HENRY F. GOLDSMITH.
